CLAIM

The ornamental design for a bar code printer, as shown and described.

DESCRIPTION

FIG. 1 is a front perspective view of the present invention.

FIG. 2 is a rear perspective view of FIG. 1.

FIG. 3 is a front elevation view of FIG. 1.

FIG. 4 is a rear elevation view of FIG. 1.

FIG. 5 is a top plan view of FIG. 1.

FIG. 6 is a right side elevation view of FIG. 1.

FIG. 7 is a left side elevation view of FIG. 1; and,

FIG. 8 is a partial front detail perspective view thereof.

The bottom of the bar code printer is not shown and is not claimed.

The broken line and dashed lines indicate disclaimed subject matter for environmental and for illustrative purposes only and form no part of the claimed design. There is no claim to portions that are not shown. The dot-dash broken line encircling the detailed view on FIGS. 1 and 8 does not form any part of the claimed invention.
